FLASK HOIST FOR FOUNDRY MOLDING MACHINES

Stanley James Gedris, Grand Rapids, Mich.

Application July 28, 1950, Serial No. 176,508

3 Claims. (Cl. 198—33)

1

This invention relates to foundry equipment and more particularly to a machine for inverting flasks containing a formed sand mold.

This application is a continuation-in-part of my copending application entitled "Molding Machine," Serial No. 723,025, filed January 20, 1947, and now abandoned.

In the preparation of foundry molds for making castings, the molds are normally made in two parts. One half of the impression of the item to be cast appears in the drag mold seated in the drag flask and the other half of the impression of the item to be cast is formed in the cope mold seated in the cope flask. It is a common practice to make the molds upon a pattern plate in which the pattern extends upwardly from the pattern plate and the sand in which the impression is made is packed down about this upwardly projecting pattern. When the mold is drawn from the pattern plate, the cavity formed by the pattern appears in the lower face of the mold. This is a satisfactory arrangement for the cope portion of the mold, but in the drag portion of the mold it is necessary to invert the mold in order to have this impression directed upwardly to mate with the impression in the cope mold. Thus, it becomes necessary to invert the drag mold after it is drawn from the pattern plate.

Numerous machines have been developed to invert the drag mold. These various machines have not proved entirely satisfactory because they are complex in their structure and, therefore, not particularly suited to foundry operations. Normal foundry operations are carried on under severe conditions including large quantities of abrasive materials and corrosive fumes. Thus, it is necessary to design all equipment for use in foundries to be simple and capable of operating under such excessively adverse conditions.

Inasmuch as most molds are formed in foundry sand, the handling of the molds must be done without sudden acceleration of the molds, shocks or jolts whereby the mold will be weakened or otherwise injured.

It is, therefore, a primary object of my invention to provide a simple mechanism for inverting a drag mold, which mechanism will operate smoothly without jarring the molds.

It is a further object of my invention to provide such a mold inverting mechanism which may be made to operate entirely automatically.

It is an additional object of my invention to provide a foundry mold inverting mechanism which will operate rapidly and accurately.

2

These and other objects of my invention will be immediately seen by those acquainted with foundry equipment upon reading the following specification and the accompanying drawings.

5 In the drawings:

Figure 1 is a sectional elevation view of my invention taken along the plane indicated by line I—I in Figure 4, and showing the flask supporting frame in position for receiving a flask before inverting the flask.

Figure 2 is a sectional elevation view taken along the same plane as Figure 1 but showing the flask supporting frame in position to release the flask after having inverted the flask.

10 Figure 3 is a plan view of my invention taken along the plane III—III of Figure 2 showing my flask supporting frame in released position.

Figure 4 is a plan view of my invention taken along the same plane as Figure 3 but showing the flask supporting frame in closed or flask gripping position.

15 Figure 5 is an enlarged fragmentary sectional view taken along the plane V—V of Figure 4.

Figure 6 is an enlarged fragmentary sectional view of my invention taken along the plane VI—VI of Figure 2.

20 Figure 7 is a flow diagram of one arrangement of automatic controls for the operation of my invention.

25 In executing the objects and purposes of my invention I have provided a flask supporting frame pivoted about one end. The frame is provided with a pair of spaced arms which are alternately closed upon the flask and spaced from the flask. When the arms are closed upon the flask, they grip the flask tightly so that the frame may be pivoted about its one end to transfer the flask from one conveyor to another conveyor and at the same time invert the flask. As soon as the flask has been inverted and deposited on the second conveyor, the frame is caused to release the flask and the frame pivots back to receive the next flask.

30 In the following description the terms "upwardly" and "downwardly" are freely used. The term "upwardly" is to be taken as meaning "upwardly" as the machine is normally used and as shown in Figures 1 and 2, and the term "downwardly" as away therefrom.

35 Referring now to the drawings in greater detail, the numeral 1 refers to a conveyor. On one side of the conveyor 1 are a pair of long, vertical standards 2 and 2a. On the other side of the conveyor 1 are a pair of short, vertical standards 3 and 3a. Beams 4 are mounted between the standards 2 and 2a and the standards 3 and 3a.

A cross beam 5 extends between the standards 2a and 3a.

Rotatably mounted on and between the beams 4 by means of the journals 6 is the shaft 10. Rigidly attached to the shaft 10 by means of the hanger straps 11 is the U-shaped frame 12 consisting of a pair of parallel sides 13 and a connecting bar 14. Parallel to the sides 13 are a pair of spaced stops 19 attached to the connecting bar 14. Pivotedly mounted at 15 to each of the sides 13 adjacent the connecting bar 14 is an arm 16. The arms 16 extend beyond the free ends of the sides 13 and at their ends remote from the pivotal mounting are connected by a double acting cylinder 17 and piston 18.

Pivotedly mounted to each of the arms 16 by means of pins 25 are a pair of fingers 30. The fingers 30 are substantially spaced from each other and from both the cylinder 17 and the connecting bar 14. Four guides 31 are mounted on the sides 13 each of which guides slidably receives one of the fingers 30. The guides 31 each have a base web 38 (Fig. 5) for spacing the fingers 30 from the arms 16. Both the base webs 38 and the sides 13 are slotted 39 to permit inward and outward travel of the pins 25 mounting the fingers 30 to the arms 16. The slots 39 are wider than the pins 25 to permit a slight play of the pins 25 because the movement of the arms 16 is rotational about the pivots 15. Likewise, the pins 25 are rigidly attached to the fingers 30 but are provided with an elongated hole in the arms 16 because of the arcuate movement of the arms.

The fingers 30 each consist of a plate 32 resting upon the base web 38 and having a hook 33 at the end of the plate remote from its supporting arm 16. The hook 33 creates a slot 34 between the hook and the plate, which slot is of the correct width to receive the rim or flange 35 of a flask 36. When seated about the flange of a flask, the hook 33 grips one face of the flange and the plate 32 grips the other face of the same flange. The guides 31 each have a central channel 37 for providing a pathway for the hooks 33.

The two guides 31 remote from the shaft 10 are each provided with a lug 26 extending across the central channel 37. The lugs 26 contact the hooks 33 for purposes which will be more fully explained under "Operation."

A spur gear 40 is rigidly attached to the shaft 10 adjacent one of the ends of the shaft 10. The gear 40 meshes with a rack 41 mounted on the end of the piston 42 of the double acting cylinder 43. The cylinder 43 is mounted on the cross member 44 extending between and supported by the vertical standards 2 and 2a. The cylinder 43, piston 42 and rack 41 are vertically disposed adjacent and substantially parallel to the vertical standard 2a. The rack 41 is urged into engagement with the gear 40 by the guide roller 45 mounted on the cross beam 5.

To one side of the shaft 10 are a pair of rails 50 constituting a track and supported by the beams 51 and legs 52. The rails 50 are shown as disposed at a right angle to the conveyor 1. However, they may be parallel to the conveyor when such an arrangement is desired. The rails 50 are spaced substantially above the conveyor 1. The exact spacing between the rails 50 and the conveyor 1 may be varied according to the requirements of the machine with which my flask turnover or inverter invention is to be used. However, the length of the hanger straps

11 and the vertical position of the shaft 10 will be affected by the vertical spacing between the rails 50 and the conveyor 1. The shaft 10 must be equi-distant between the horizontal plane of the lower flange 35 of the flask 36, when the flask is seated on the rails 50, and the horizontal plane of this same flange of the flask when the flask has been inverted and the flask seated on the conveyor 1. The length of the hanger straps 11 will depend upon the spacing between the rails 50 and the conveyor 1.

By reason of the base web 38 of the guides 31, the fingers 30 will be spaced below the tops of the rails 50 sufficiently that the slot 34 between the hook 33 and the plate 32 will register with the flange 35 of a flask 36 seated upon the rails 50. The base webs 38 permit the fingers to seat down between the rails 50 when the sides 13 of the frame 12 are positioned over the rails 50.

The frame 12 is provided with a stop 60 adjacent the free end of each of the sides 13. The stops 60 project both above and below the sides 13, whereby at one end of the frame's travel the stops 60 will contact the abutments 61 on the conveyor 1 and at the other end of the frame's travel will contact the beam 51 remote from the shaft 10.

It will be understood that my turnover frame is designed to be used with other units of foundry equipment. Therefore, the design and operation of the conveyor 1 and the rails 50 are not described in detail since they may vary from one installation to another. The only thing in relation to the conveyor 1 and the rails 50 which is of importance to my improved turnover frame is the vertical spacing between these parts and their location with respect to the shaft 10.

Operation

In the operation of my turnover frame, a flask 36 is first moved into position on the rails 50 whereby the frame 12 may seat down around it. This may be done manually or mechanically, such as by the step by step conveyor shown in my copending application entitled "Conveyor for Foundry Molding Machine." The particular means used to position the flask on the rails 50 is unimportant to this invention.

After the flask has been positioned on the rails 50, the frame 12, with the arms 16 at maximum spacing, is pivoted about the shaft 10 until it seats down around the flask 36 and the stops 60 contact the beam 51. In this position, the lower flanges 35 of the flask 36, as the flask is positioned on the rails 50, are in register with the slots 34 of the fingers 30. The cylinder 17 is then actuated to withdraw the piston 18, rapidly drawing the arms 16 toward each other. This closing together of the arms 16 forces the fingers 30 to seat about the flanges 35 on each of two opposite sides of the flask 36.

Once the flask 36 has been securely grasped by the fingers 30, the cylinder 43 is actuated to withdraw the piston 42 causing the shaft 10 to rotate and the frame 12 to be pivoted about the axis of the shaft until the flask 36 comes to rest on the conveyor 1. In its travel from the rails 50 to the conveyor 1, the flask 36 is inverted. The stops 19 limit the travel of the flask 36 toward the connecting bar 14 as this operation is carried out. The cylinder 17 is then actuated to eject the piston 18, spreading the arms 16 and releasing the flask 36. Should one of the arms 16 offer more resistance to being moved

than the other, it will move away from the flask until the hook 33 of its finger 30 remote from the shaft 10 contacts the lug 26. Upon contacting the lug 26, further movement of that arm 16 will be prevented and the other of the arms 16 will have to move under the urging of the cylinder 17. The cylinder 17 is designed to have a maximum stroke no greater than the maximum displacement necessary to engage and disengage the fingers 30.

As soon as the arms 16 have been spread apart to release the flask 36, the cylinder 43 is actuated to eject the piston 42. This pivots the frame 12 back to its initial position on the rails 50. In the meantime another flask 36 will have been positioned on the rails 50 to be received by the frame 12. While the frame 12 is receiving a new flask from the rails 50, the preceding flask will be removed by the conveyor 1.

The cylinders for powering my turnover frame may be actuated pneumatically or hydraulically. It is also possible to substitute a partially or wholly electrical operating system for the pneumatic or hydraulic system shown. The coordination and operation of the various cylinders actuating my improved turnover may be manual or automatic. Numerous different valve and flow arrangements may be made to control this actuation. For the purpose of completeness I shall illustrate and describe one particular valve arrangement capable of automatically regulating the operation of my turnover. Again for the purpose of brevity I shall illustrate this valve arrangement as though the actuating medium were compressed air. However, this particular arrangement and actuating medium is not to be considered as a limitation upon my invention.

Compressed air is supplied from any suitable source 100 (Fig. 7), such as a tank, or from the compressed air lines of a machine with which my turnover is to be used and coordinated. The conduit 101 leads the air to a master valve 102. By means of the conduit 103, air is led from the conduit 101 to the regulator valve 104. The regulator valve 104 is mounted on the rail 50 remote from the shaft 10. When the frame 12 is resting upon the rails 50, the frame depresses the plunger 80 causing air to pass through the conduit 105 to the actuator 81 on the valve 102. This closes the valve 102. Simultaneously air is admitted by the valve 104 through the conduit 106 to the actuator 82 which thereupon sets the valve 107 to admit air via the conduits 108 and 109 to the lower end of the cylinder 43. Simultaneously the valve 107 will be caused to open to admit air to the cylinder 17 via the conduit 111. The valve 107 is supplied air from the valve 102 by the branch conduit 110a of the conduit 110. However, since the valve 102 is closed, no air will be admitted to the valve 107 or to any conduit depending upon valve 107 for air. In this position of the machine, the pistons 42 and 48 are both in fully extended position.

The valve 102 is then opened either manually or by means of an actuator operated from a machine used in conjunction with my turnover and the operation of which is coordinated with my turnover. The valve 102 then admits air to the valve 107 which, in turn, admits it to both the cylinders 43 and 17. A restrictive unit 83 is provided in the conduit 109 between the junction of the conduit 109 and the conduit 108. By this means the cylinder 17 is enabled to complete its full withdrawal stroke before the cylinder 43 starts any appreciable movement.

The operation of the cylinder 43 withdrawing the piston 42 lifts the frame 12 from the plunger 80 causing the valve 104 to shut off the flow of air to conduits 105 and 106 and to reset the actuator 81 ready to again close the valve 102 and to reset the actuator 82 ready to open the valve 107. By reason of the restrictor 83, the movement of the piston 42 is gradual, eliminating any shock to the sand mold within the flask 36.

As the frame 12 lays the flask 36 upon the conveyor 1, the plunger 84 of the valve 112 is first depressed. The valve 112 is supplied by air directly from the valve 102 by the branch conduit 110b. Depressing of the plunger 84 admits air through the conduit 113 to the actuator 85. The actuator 85 then operates the valve 107 to shut off the air supply through the conduit 108 to the lower end of the cylinder 43 and then shuts off the air supply via the conduit 111 to the piston end of the cylinder 17. As the valve 107 is closed, it opens the conduits 111 and 109 to the exhaust port 114 whereby air is bled from the cylinders 17 and 43.

Upon further lowering of the frame 12, the plunger 119 will be depressed admitting air first to the conduit 115 whereby the piston 18 will be ejected by the cylinder 17 and the flask 36 released. Simultaneously the plunger 84 will cause the air to be admitted to the conduit 116 reversing the direction of movement of the piston 42 and starting the frame 12 back toward the rails 50. The flow restrictor 87 in the conduit 116 will prevent the cylinder 43 from reversing its movement prior to the actuation of the cylinder 17. When the frame 12 again is seated upon the rails 50, depression of the plunger 80 causes air to be admitted through the conduit 105 to close the valve 102 and through the conduit 106 to open the valve 107. By means of the conduit 117 air will simultaneously be admitted to the actuator 86 to reset the plungers 84 and 85 and the valve 112 ready for the next passage of the frame 12. The valve 112, when reset, will open the conduits 116 and 115 to the exhaust port 118 whereby the upper end of the cylinder 43 and the non-piston end of the cylinder 17 may be bled of air, respectively.

The structure of the various cylinders, valves, actuators and flow restrictors is not described in detail because there are many conventional designs of this type of equipment available, and the particular internal structural arrangement of this equipment forms no part of this invention.

Except for the flow diagram in Figure 7, I have not shown nor described the arrangement of the various conduits in relation to the structural illustration of my turnover. This arrangement may be made in many different ways, and the inclusion of the various conduits and valves upon the drawings will make my invention more difficult to understand.

I have illustrated and described a machine for removing a foundry flask from one track and placing it upon another. In the operation of transferring the flask from one track to another, the mold within the flask is inverted whereby a drag mold having a downwardly directed mold cavity may be caused to have an upwardly directed mold cavity ready to receive the mating cope mold. The machine is designed to move the flask without impairing the mold by shocks or sudden acceleration. At the same time the mechanism may be made to operate swiftly and entirely automatically.

Numerous modifications of my invention may be made without departing from the principle of my invention. Each of these modifications is to be considered as included in the hereinafter appended claims unless these claims by their language expressly provide otherwise.

I claim:

1. In a flask turnover for a foundry flask having an outwardly extending rim, a first conveyor and a second conveyor, said first conveyor being disposed above said second conveyor, the combination comprising: a hinge member including a shaft; a frame having sides and ends; said frame having one end affixed to said shaft of said hinge member and the other of its ends free; a pair of arms, one on each side of said frame; each of said arms pivotally mounted to said frame adjacent said hinge member; means affixed to the other of the ends of each of said arms for alternately substantially aligning said arms with said sides of said frame and spacing said arms substantially from said sides at the free ends of said frame; fingers mounted on each of said arms and movable therewith for receiving said rim of said flask; means for pivoting said frame from a position horizontal to said first conveyor to a position horizontal to said second conveyor and returning said frame to a position horizontal to said first conveyor.

2. In a flask turnover as described in claim 1 wherein said fingers each have walls defining a slot for receiving said rim of said flask; a plurality of guides on said sides of said frame, each of said guides slidably receiving one of said fingers.

3. In a flask turnover as described in claim 1 wherein said fingers each have walls defining a slot for receiving said rim of said flask; a plurality of guides on said sides of said frame, each of said guides slidably receiving one of said fingers; means on at least one of said guides on each of said sides for contacting the fingers received in said guides and limiting the diverging pivotal movement of said arms.

STANLEY JAMES GEDRIS.
